UNITED STATES PATENT OFFICE.

JAMES H. CLARK, OF DETROIT, MICHIGAN, ASSIGNOR TO BRIGGS MANUFACTURING COMPANY, OF DETROIT, MICHIGAN, A CORPORATION OF MICHIGAN.

CHASSIS-FRAME CONSTRUCTION.

Application filed June 14, 1926. Serial No. 115,981.

The invention relates to a frame construction and more particularly to a combination chassis and sill construction wherein the same frame structure constitutes both the chassis and body sills.

The invention has therefore as one of its objects to eliminate the body sill and to employ in its place a singular member constituting both the body sill and the chassis side rail whereby a more economical and otherwise satisfactory structure from a commercial standpoint may be obtained.

Another object of the invention is to provide a chassis or frame construction involving main and supplemental or auxiliary sill or rail members and to form the supplemental or auxiliary rail members in units including two substantially longitudinally arranged side rails with separate end units connected thereto and to the main rail members for reinforcing the latter and for adding rigidity to the completed structure.

Another object of the invention resides in providing a construction wherein it is possible to use relatively light gauge non-load-supporting wheel housings, the main and the supplemental frame members being shaped to clear the wheels and to support the load at this point.

Another object and advantage of the invention is obtained by forming the rear portions of the main side rails separate from the remaining structure so that they may be reversed with the channels thereof presented outwardly to provide a greater or increased width between these rear side rails whereby the springs may be suspended on the inside of the frame.

Numerous other objects, advantages and novel details of construction will be made more apparent as this description proceeds, especially when considered in connection with the accompanying drawings wherein;

Figure 1^a is a plan view of the front half of a chassis or frame construction in accordance with this invention.

Figure 1^b is a plan view of the rear half of a chassis or frame construction in accordance with this invention.

Figure 2 is a side elevation of the structure illustrated in Figure 1.

Figure 3 is a rear end elevation of the structure illustrated in Figure 1.

Figure 4 is an enlarged fragmentary sectional view taken substantially on the plane 55 indicated by line 4-4 in Figure 1 and

Figure 5 is an enlarged fragmentary sectional view taken substantially on the plane indicated by the line 5-5 in Figure 1.

Referring now particularly to the drawings wherein like characters indicate like parts it will be noted that the frame consists essentially of a main frame 10 and a supplemental or auxiliary frame 11 extending substantially parallel thereto throughout its length, with the outer supplemental or auxiliary frame 11 arranged below the plane of the main frame for reasons which will appear more fully hereinafter.

The main frame consists of a pair of front side rails 12 and a pair of rear side rails 13. The rails 12 and 13 are, as is customary, of a substantially U-shape in cross section, the rails 12 having their channels presented inwardly while the rails 13 are reversed so as to present their channels outwardly, a pair of the rails 12 and 13 constituting together a main side rail or sill and being spliced together as indicated at 14. By reversing the position of the channels of the rear rail sections 13 a greater width between these rails is obtained for suspending the springs indicated in dotted lines at S. The main sills or side rails are united adjacent their forward ends by means of cross members 15 two of such cross members being as shown in the illustrative embodiment of the invention, which construction lends itself admirably to supporting the motor of the vehicle (not shown). A further cross member 16 is provided which also extends into the channels of the rail members 12, being riveted or otherwise fastened to these rails and further united thereto as for instance by means of gusset plates 17.

The supplemental or auxiliary frame 11 consists essentially of five units including a pair of substantially longitudinally extending rails 18 provided with extensions 18', an outer front end rail 19, and a rear end rail 20 and a pair of sub or extension rail members 21. The front end rail 19 is substantially U-shaped in plan view and is united, as by means of splicing indicated at 22 to the sub or extension rails 21. The front end rail 19 is shaped to ex-

tend under and clear the forward ends of the main side rails 12 and is suspended and supported therefrom by means of gusset members 23 which are substantially L-shaped in cross section and which are further shaped to provide end flanges 24 secured respectively to the tops of the rails 12 and 19 and with lateral flanges 25 which engage the vertical sides or bases of these rails, see particularly Figures 1 and 2. The forward end rail 19 is connected adjacent its ends to the main rails 12 by means of supplemental cross members 26 which preferably extend angularly and rearwardly, as clearly illustrated in Figure 1. The sub or extension rails 21 are connected to the main rails 12 by means of cross frame members 27. It will be noticed, from Figure 1, that the rear ends of the extension rails 21 overlap or extend beyond the forward ends of the rails 18 but that these adjacent ends are laterally spaced.

The supplemental longitudinal side rails 18 are connected to the main side rails by a plurality of auxiliary cross members 28, arranged in longitudinal spaced relation to one another. Inasmuch as the supplemental rails 18 are arranged in a plane below the main side rails, the cross members connecting these parts must be of a shape substantially similar to that illustrated in Figure 5 of the drawings. Obviously the customary gusset plates 29 will be associated with the cross members 28 to insure the desired rigidity of the connection between the parts.

The rear end rail members 20 is also substantially U-shaped in plan view and overlaps the extensions 18' of the rails 18 and is secured thereto as indicated at 30. It should be noted, in passing, that the rails 18 adjacent their ends are bent outwardly from the general longitudinal plane thereof so as to provide a greater clearance space between the main and supplemental rails at this point. Accordingly the ends of the rear end rail member 20 are also bent outwardly at their ends so as to place these ends in alignment for proper connection with the ends of the rails 18. Cross members 31 connect the rear end rail member 20 to the main rail members 13 adjacent to rear ends of the latter, these main rail members being also connected to a transverse frame member 32 which extends laterally beyond these rail members and is connected as at 33 to the rear end rail 20. The ends of the rails 13 may be flanged as at 34 for attachment to the frame member 32 and also suitable gusset plates 35 may be employed for adding rigidity to the construction at this point. Braces 36 connected to the rear end rail 20 stand outwardly for connection with the transverse frame member 32.

The extension 18' of each rail 18 is of semi-circular configuration but U-shaped in cross section similar to the rails 18 and 20 to which

it is connected. The upward curve of the extension rail 18' is sufficient in height to clear the adjacent axle and wheel and this rail constitutes a part of the wheel housing. The adjacent portion of the corresponding main side rail 13 is also formed with an upwardly directed curved portion and the lower flange of the rail throughout this curved portion is bent downwardly as indicated at 37, see particularly Figures 2 and 5. A thin metallic covering 38 rests upon the inwardly directed flanges at the upper edges of the curved portions of the rails 18 and 13 to complete the wheel housing. It is obvious, however, that the covering 38 is of a protective character only and does not support any load, the load being taken up entirely by the frame members.

The reference character 39 indicates a tubular transversally arranged torsional member which extends from one side of the chassis frame to the other, being rigidly connected at its ends as at 40 to the overlapping portions of the rails 18' and 20. In view of the fact that the rails constituting the supplemental or auxiliary frame are arranged below the plane of the main frame the tubular torsional member 39 may extend directly across the chassis frame without any portions thereof being off-set. For connecting the torsional member to the rails 13 of the main frame, there is provided brackets 41 which depend from the rails 13 and are provided with flanged apertures 42 through which this torsional member extends. Thus the torsional member is rigidly connected at its ends to the auxiliary or supplemental frame and intermediate its ends to the main frame.

Extending transversally of the rail members 12 and below the plane thereof is a tubular torsional member 43. This tubular member is rigidly connected to the rail members 12 by means of brackets 44 which are secured to said rails and depend downwardly therefrom. These brackets are provided with flanged apertures 45 through which the tubular member 43 extends, the ends of this member being provided with coupling sleeves 46 formed with a circumferential radially extending flange 47. The reference character 48 indicates a pair of co-extensive tubular torsional members formed preferably in two sections or halves longitudinally united and with a circumferentially radially directed flange 49 at one end which is connected to the flange 47 aforescribed and at this other end with a radial flange 50 which abuts the base of the channel-shaped rail 18. The space between the overlapping ends of the rail members 18 and 21 is spanned by a torsional member 51 also preferably formed in two sections or halves and formed with radially extending flanges 52 and 53 at the ends thereof. The flange 52 is arranged in axial alignment with the flange 50 but bears

115
120
125
130

against the other face of the base of the rail 18 whereupon these parts may be secured together by welding or by rivets as desired. The outer end of the tubular member 51 is 5 secured by its flange 53 to the end of the rail 21. Thus it will be seen that a continuous transverse tubular torsional member is provided which extends from the rail member 21 on one side of the chassis frame to the 10 corresponding member on the other side, this torsional member being formed of a center section 43 united at its ends with extension sections 48 which in turn are connected to the extensions 51 whereby the rails 21, 18 and 15 12 at both sides of the chassis frame are rigidly interconnected.

By reason of the transversely arranged torsional members, the front and rear end rails and the connection between these parts 20 and the main rail members a structure of great rigidity is obtained and one which is fully capable of withstanding weaving strains and stresses and other disastrous loads imposed upon the chassis frame. The 25 longitudinally spaced supplemental frame cross members extending between the main and supplemental frames also function to increase the rigidity and strength of the completed structure.

30 By reversing the rear main side rail sections 13 greater clearance is provided between these rails and sufficient space is left to mount the springs. Furthermore by the construction herein described a sufficient 35 clearance is also provided between the main and supplemental rail members near the rear end thereof, to accommodate the wheels it being understood that the main and supplemental side rails are substantially continuous 40 from the front to the rear of the chassis and are curved upwardly to clear the rear axle and wheels so as to take the load at this point and to make it possible to employ relatively thin wheel housings which carry no load 45 whatsoever.

While one embodiment of the invention has been described and illustrated herein somewhat in detail, it will be readily apparent to those skilled in this art that the principles of this invention are capable of expression in various forms wherein details of construction other than those herein shown are employed and accordingly reservation is made to make such changes in the essential 55 and all of the non-essential details as may come within the purview of the accompanying claims.

What I claim as my invention is:

1. In a frame construction, inner and outer 60 frame members and a transverse extension on said outer frame member connecting the same at the front ends thereof and extending under said inner frame members in the same horizontal plane as the said outer frame 65 member.

2. In a frame construction, an inner frame member, an outer frame member having its forward portion lying in a plane below that of the inner frame member and a substantially transversely arranged frame member 70 connecting the front ends of said outer frame members and connected to said inner frame members and extending thereunder.

3. In a frame construction, inner and outer longitudinal sill members and a substantially 75 U-shaped member connected to the ends of said outer longitudinal sill members and extending forwardly therefrom under said inner longitudinal sill members.

4. In a frame construction, a pair of spaced longitudinal inner main sill members, a pair of substantially parallel auxiliary outer sill members lying in a plane below that of the main frame members and a straight tubular torsional cross member extending between said auxiliary sill members and depending brackets on said main sill members connecting the same to said cross members. 85

5. In a frame construction, spaced main 90 and auxiliary frame members each having a corresponding portion thereof shaped to provide a wheel housing.

6. In a frame construction, spaced main 95 and auxiliary frame members each having a corresponding portion thereof shaped to provide a wheel housing frame and a covering secured to said frame.

7. In a frame construction, a pair of spaced longitudinally extending main and auxiliary sills, said sills having corresponding portions thereof off-set upwardly and a wheel housing cover supported on said off-set portions. 100

8. In a frame construction, a pair of 105 spaced longitudinally extending main and auxiliary sills, said sills having corresponding portions thereof off-set upwardly and laterally and a wheel housing cover supported on said off-set portions.

9. In a frame construction, a pair of spaced longitudinally extending main sill members, a pair of substantially parallel auxiliary sill members spaced from said main sill members, each pair of main and auxiliary sill members having corresponding portions thereof upwardly and laterally off-set intermediate their lengths to provide a wheel clearance and a wheel housing cover 115 of relatively light gauge material secured to 120 said off-set portions.

10. In a frame construction, an inner main frame member, an outer auxiliary frame member arranged in a relatively lower plane than said inner frame member, a tubular torsional member extending from one side of said outer frame member to the other below the plane of said inner frame member and gusset members connecting said inner frame members to said tubular member. 125 130

11. In a frame construction, an inner main frame member, an outer auxiliary frame member spaced from said inner frame member at the front, back and sides thereof, and having its front portion extending beneath the main frame member and secured thereto.
12. In a frame construction, an inner main frame member, an outer auxiliary frame member spaced from said inner frame member and having its forward side portions slanting downwardly below said inner frame member, the front portion of said auxiliary frame member passing under said inner frame member and secured thereto.
13. In a frame construction, an inner main frame member, an outer auxiliary frame member spaced from said inner frame member and being in a plane lower than that of the inner frame member, the front portion of said auxiliary frame member passing under said inner frame member and secured thereto.
14. In a frame construction, a pair of spaced longitudinal main sill members, a pair of substantially parallel auxiliary sill members, a straight tubular cross member extending between said auxiliary sill members and depending brackets on said main sill member connecting the same to the cross member, said cross member consisting of a central unit having its ends formed into radially extending flanges, and outer units having corresponding radially extending flanges at their inner ends secured to said first mentioned flanges and having flanges at their outer ends secured to said auxiliary sill members.
15. In a frame construction, a pair of spaced longitudinal main sill members, a pair of outer substantially parallel side auxiliary sill members terminating short of said main sill members, a front auxiliary sill member having rearwardly extending portions spaced from and overlapping said side auxiliary sill members, a cross member secured to said main sill members and having its ends secured to said side auxiliary sill members, and torsional members substantially co-planar with said cross members and secured to the overlapping portions of said side and front auxiliary sill members.
16. In a frame construction, a pair of spaced longitudinal main sill members, a pair of outer substantially parallel side auxiliary sill members terminating short of said main sill members, a front auxiliary sill member having rearwardly extending portions spaced from and overlapping said side auxiliary sill members, a cross member secured to said main sill members and having its ends secured to said side auxiliary sill members, and torsional members substantially co-planar with said cross members and having their end portions provided with radially extending flanges secured to the overlapping portions of said side and front auxiliary sill members.

In testimony whereof I affix my signature.

JAMES H. CLARK.
